[57] CLAIM

The ornamental design for a faucet spout, substantially as shown and described.

DESCRIPTION

FIG. 1 is a perspective view of a faucet spout showing our new design;

FIG. 2 is a right side elevational view thereof, the left side being a mirror image of the right side shown;

FIG. 3 is a top plan view thereof;

FIG. 4 is a front elevational view thereof;

FIG. 5 is a rear elevational view thereof;

FIG. 6 is a perspective view of a modified form of the faucet spout shown in FIG. 1;

FIG. 7 is a right side elevational view of FIG. 6, the left side being a mirror image of the right side shown;

FIG. 8 is a top plan view of FIG. 6;

FIG. 9 is a front elevational view of FIG. 6;

FIG. 10 is a rear elevational view of FIG. 6; and

FIG. 11 is a bottom plan view of FIG. 6.

The broken line representation of a base for the faucet spout shown in FIGS. 6 through 11 is for purposes of illustration only and forms no part of the claimed design.
